UNITED STATES PATENT OFFICE

161,459

MUG

Bernardo H. Karmen, Banning, Calif.

Application March 29, 1950, Serial No. 8,854

Term of patent 7 years

(Cl. D36—8)

To all whom it may concern:

Be it known that I, Bernardo H. Karmen, a citizen of the United States of America, and a resident of the city of Banning, Riverside County, State of California, have invented a new, original, and ornamental Design for a Mug, of which the following is a specification, reference being had to the accompanying drawing, forming a part thereof.

In the drawing,

Fig. 2 is a top plan view thereof.

Fig. 3 is a side elevational view opposite to that of Fig. 1.

I claim:

The ornamental design for a mug, substantially as shown.

BERNARDO H. KARMEN.
